US00D807337S

(12) **United States Design Patent** (10) **Patent No.:** **US D807,337 S**
(45) **Date of Patent:** **** Jan. 9, 2018**

(54) **COVER FOR AN ELECTRONIC DEVICE**

(71) Applicant: **SAMSUNG ELECTRONICS CO., LTD.**, Suwon-si (KR)

(72) Inventors: **Yoonyoung Kim**, Seongnam-si (KR); **Keemoon Lee**, Yongin-si (KR); **Kyunghoon Kim**, Seoul (KR)

(73) Assignee: **Samsung Electronics Co., Ltd.**, Suwon-si (KR)

(**) Term: **15 Years**

(21) Appl. No.: **29/569,033**

(22) Filed: **Jun. 23, 2016**

(30) **Foreign Application Priority Data**

Dec. 24, 2015 (KR) 30-2015-0066094

(51) LOC (11) Cl. **14-03**

(52) U.S. Cl.

USPC **D14/250**

(58) **Field of Classification Search**

USPC D14/250; 455/575.8

CPC A45C 11/00; A45C 2011/002
